UNITED STATES PATENT OFFICE.

WILLIAM D. WHITE, OF WORCESTER, MASSACHUSETTS, ASSIGNOR TO HOLYOKE MACHINE COMPANY, OF WORCESTER, MASSACHUSETTS, A CORPORATION OF MASSACHUSETTS.

STOP FOR WATER-WHEELS.

971,095.

Specification of Letters Patent. Patented Sept. 27, 1910.

Application filed February 18, 1907. Serial No. 357,889.

To all whom it may concern:

Be it known that I, WILLIAM D. WHITE, a citizen of the United States, residing at Worcester, in the county of Worcester and 5 Commonwealth of Massachusetts, have invented certain new and useful Improvements in Stops for Water-Wheels, of which the following is a specification, accompanied by drawings forming a part of the same, 10 in which—

Figure 1 is an end view of a water wheel governor with a stop embodying my invention applied thereto, and Fig. 2 is an enlarged view of a portion of a governor, 15 partly in section, showing my improved stop also in section.

Similar reference letters and figures refer to similar parts in the different views.

My invention relates to a stop for water 20 wheels by which upon the completion of an electric circuit the water is immediately shut off from the water wheel, thereby stopping the wheel at once, and it consists in the construction and arrangement of parts as herein 25 inafter described and pointed out in the annexed claims.

I have shown my stop attached to a water wheel governor of the class shown and described in Letters Patent of the United 30 States, No. 754,469, issued to Nathaniel Lombard March 15, 1904, to which patent reference may be had for a more detailed description of the parts of the governor not herein described. As fully described in said 35 Letters Patent and as will be well understood by persons conversant with hydraulic governors, a governor of this class comprises means for opening or closing the water gate according to the speed of the water 40 wheels, and its operative parts are actuated by a piston equipped power cylinder 1, to which fluid under pressure is admitted upon either side of the piston by means of a reciprocating spool shaped valve 2, inclosed in a valve case 3, and carried upon a valve 45 stem 4. The valve stem 4 is connected by a system of levers with a weighted governor 5 of the centrifugal type inclosed in the rotating belt pulley 6, whereby the speed 50 of the belt pulley 6 as driven by the water wheel will cause the valve 2 to reciprocate to open or close the ports 7 and 7^a through which fluid under pressure is admitted to either end of the power cylinder 1. This 55 portion of the mechanism forms no part of my present invention, as it is now in common use in water wheel governors of this class and is fully described in the patent to Lombard aforesaid No. 754,469.

It is the object of my present invention to 60 provide means by which the valve 2 may be moved instantaneously in one direction at will, in order to admit fluid to the power cylinder in order to close the water gate and stop the water wheel, and my invention is 65 applicable to any type of governor which comprises a piston equipped cylinder and a controlling valve for admitting fluid under pressure thereto. The system of levers by which the valve stem 4 is connected with the 70 centrifugal governor 5 comprises a lever 8 pivoted at its lower end to the framework of the machine and having its upper end pivotally connected with a shell 9 through which the valve stem 4 passes. Within the shell 9 75 and adjustably attached to the valve stem 4 is a nut 10 which is held stationary with reference to the shell 9 by a latch 11. A check nut 12 holds the nut 10 in position when the valve stem and valve 2 have been properly 80 adjusted in the valve case 3. The action of the centrifugal governor 5 through its lever connection reciprocates the shell 9 which carries with it also the nut 10 and the valve stem 4, thereby opening and closing the ports 7 85 and 7^a. The end 13 of the latch 11 is provided with an armature 14 which, when the magnet 15 forming part of an electric circuit is energized by the completion of the circuit, is drawn down, thereby rocking the latch and 90 releasing the nut 10, which is pushed out of the shell 9 by the spiral spring 16 until its movement is checked by the contact of the set screw 17 and the shoulder 18. This moves the valve stem and valve in the proper 95 direction to open that port which is designed to admit fluid to the power cylinder to close the water gate upon which the entire power is shut off from the water wheel. It is thus possible by merely touching a button or by 100 any other convenient way of completing the electric circuit anywhere in a mill to stop immediately the motion of the water wheel and all the machinery driven by it. When the parts are restored to their normal position, 105 and the electric circuit broken, the nut 10 is again locked by the latch 11 and the valve 2 brought into proper relation to the ports 7 and 7^a to resume the operation of the governor.

I claim,

1. The combination of a power controlling valve, an integral valve stem for said valve, a governor for operating said valve stem, a shell connected with said governor surrounding said valve stem, open at one end, connecting means adjustably attached at said open end to said valve stem and detachably held in said shell, and a spring held in said shell arranged to move said valve stem out of said shell when said detachable means are released, thereby operating said valve independently of the operation of said governor.
2. In a governor of the class described, the combination with a power controlling valve, and a valve stem carrying said valve, of a spring having its tension applied to move said valve stem in one direction, a nut adjustably held on said valve stem, and a latch engaging said nut to hold the valve stem against the tension of said spring, and means for releasing said latch.

3. In a governor of the class described, the combination of a valve for controlling the application of power to the governor, a screw 25 threaded valve stem carrying said valve, a nut engaging said valve stem, a spring pressing against said nut to move said valve stem in one direction, means for holding said nut from movement by the spring, and means 30 for releasing said nut at will.

4. In a governor of the class described, the combination with the stem of a power controlling valve, of a nut held on said stem, a sleeve inclosing said nut, a spiral spring interposed between said sleeve and said nut, a latch held by said sleeve and engaging said nut, and means for releasing said latch at will.

Dated this 16th day of February 1907.
WILLIAM D. WHITE.
